COMBINED WARNING LIGHT AND SIGN FOR EMERGENCY VEHICLES

Earl W. Gosswiller, Chicago, Ill., assignor to Federal Sign and Signal Corporation, Blue Island, Ill., a corporation of New York

Filed Sept. 9, 1963, Ser. No. 76,508

Term of patent 14 years

(Cl. D48—32)

Fig. 1.

Fig. 2.

Fig. 3.

FIGURE 1 is a front elevational view of a combined warning light and sign for emergency vehicles showing my new design, the rear view thereof being the same as the front;

FIGURE 2 is an elevational view of one side thereof, the other side view being the same; and

FIGURE 3 is a top view thereof.

The dominant features of my design reside in the portions shown in full lines.

I claim:

The ornamental design for a combined warning light and sign for emergency vehicles, substantially as shown and described.
